WASTE CONTAINER

John P. English, Northbrook, and Joseph Magarinos, Chicago, Ill.

Application October 11, 1952, Serial No. 314,359

8 Claims. (Cl. 34—69)

1

This invention relates to waste containers, and more particularly to such containers which are adapted to use in places where the waste material contains inflammable substances.

One object of the invention is to provide an improved container for waste material which may be of a combustible nature, such as oily rags or the like. In numerous places, such as printing or paint shops, factories, automobile repair shops, or service stations, for example, rags are frequently used for cleaning excess oil or grease and paint from equipment or the like, and for such rags, when discarded, containers which protect the contents against accidental ignition while permitting suitable aeration thereof are desirable. The present container is designed not only to reduce danger of accidental ignition of the inflammable contents, but also to provide for ventilation of the contents, and hence the removal of readily vaporizable substances, thereby reducing the danger of spontaneous combustion where the refuse contains rapidly oxidizable oils, for example.

Another more specific object of the invention is to provide a container or holder for a receptacle or receptacles for oily rags or like refuse, the container and receptacle or receptacles being so constructed and arranged as to provide for the effectual ventilation of the receptacle contents.

An additional object of the invention is to provide a container or holder for one or more waste receptacles and having a drip pan which is adapted to receive fluid drainage from the contents of the receptacles.

An additional object of the invention is to provide, in a container for waste holding receptacles, a motor operated ventilating means therefor.

Other objects of the invention relate to various features of construction and arrangement of parts which will be apparent from the consideration of the following specification and accompanying drawings wherein:

Figure 1 is a vertical sectional view of a refuse holder which is illustrative of one embodiment of the present invention;

Fig. 2 is a fragmentary sectional view wherein the section is taken substantially on line 2—2 of Fig. 1;

Fig. 3 is an enlarged fragmentary sectional view taken substantially on line 3—3 of Fig. 1, and illustrating a detail of my preferred structure;

Fig. 4 is a sectional view taken substantially on line 4—4 of Fig. 1;

Fig. 5 is a broken sectional view taken substantially on line 5—5 of Fig. 1;

2

Fig. 6 is an enlarged fragmentary vertical sectional view taken substantially on line 6—6 of Fig. 4;

Fig. 7 is a fragmentary sectional view taken substantially on line 7—7 of Fig. 4 illustrating one preferred type of handle in raised position and in dotted lines showing the handle in a released or pendent position;

Fig. 8 is a fragmentary front elevational view of one of the handles of the type shown in Fig. 7; and

Fig. 9 is an enlarged fragmentary vertical sectional view through a portion of a container side wall illustrating, as a modification of the above-described structure, a motor operated fan for providing forced circulation of air through the container.

In Fig. 1 of the drawings, a container or holder indicated generally by the numeral 10 is shown which preferably is of cylindrical construction and is provided with a removable cover 11. The cover is imperforate so as to exclude from the contents, when the cover is in position, accidentally dropped matches, cigarettes, or the like which might ignite inflammable contents of the container. The bottom 12 of the container preferably is provided with a pair of skids 13 which space the container from the floor and enable it to be readily picked up for movement by either a power or manually operated lift truck, or the like. The container body or side wall is provided with louvered openings 14 which, in the disclosed structure, are arranged in vertical rows and are of adequate area to enable relatively free cross ventilation through the container. Louvers 15 for the openings, as shown in Fig. 6, prevent lighted matches, cigarettes, or the like from being dropped accidentally into the covered container and at the same time permit free circulation of air through the container.

The openings 14, as shown in Fig. 4, are arranged in four vertical banks. Disposed between adjacent banks of the louver openings are relatively imperforate wall portions 16 to the inner sides of which are secured, as by welding, four vertical perforate ribs or spacers 17 which prevent excessive off-setting from a central position of a refuse holding receptacle or receptacles within the container. Secured to two opposed imperforate sections 16 of the container are handles 18, shown in detail in Figs. 7 and 8. The handles are swingably attached to the respective sections 16 by clips 19 which, in the present instance, are secured to the container by rivets, or spot welded thereto if desired. As shown in

dotted lines in Fig. 7 and in Figs. 4 and 8, the handle normally hangs in pendent position, but can be swung outwardly to the full line position shown in Fig. 7 when manually grasped, in which latter position an intermediate portion 18a engages the container wall for limiting further upward movement of the hand grip portion. The handles 18 drop to the pendent dotted line position shown in Fig. 7 when released.

The container 10 is designed to hold one or more receptacles or baskets into which oily rags or like refuse material may be deposited. In Fig. 1 of the drawings, the container is shown with two such baskets which are of identical construction and each designated by numeral 20. The baskets or receptacles are of foraminous construction, preferably made principally of wire mesh material, although they may be made of perforated sheet metal. In the structure shown, the receptacles are provided with side wall reinforcing ribs or straps 21 of sheet metal as well as an upper ring 22 defining the open upper end. Base ribs 23 are shown which extend across the bottom of the basket. The base ribs 23 of my disclosed baskets are of inverted channel form constituting runners. These runners 23 are attached, preferably by spot welding, to the reinforcing ribs or straps 21 and the latter are attached to the ring 22 by welding or other suitable means.

For the purpose of preventing the accumulation of a thick air resistant mass or masses of oily rags or other material within a basket or baskets, I have provided the baskets with diametrically disposed, raised base portions 24 which are made of a foraminous material, such as wire mesh of inverted U-shape and located above and intermediate the runners or skids 23, as shown in Fig. 4. These members 24, in the form thereof illustrated, extend diametrically across the bottoms of the baskets, are secured to the sides and bottoms of the baskets and are aeration aids in that they increase the surface areas of the masses of rags in the baskets which are exposed directly to the air flowing within the container. While but one such transverse raised member 24 is shown in each basket, more may be provided if desired, or there may be an arrangement of two of the same disposed transversely of each other if preferred. These raised formations 24 may also be formed as raised integral portions of the basket bottoms.

For supporting the lower basket 20 in the container, two laterally spaced and parallel rods 25 and 26 are utilized in my disclosed embodiment. These rods extend through apertures provided in the side walls of the container 10 and each, as shown in Fig. 1, has a ring shaped handle 27 at one end and each, at the opposite end, is provided with an aperture 28 for receiving a removable pin or key 29 (see Fig. 1) which is attached for convenience and against loss to the exterior wall of the container 10 by a short chain 30 or like flexible member. As shown in Fig. 4, the two rods 25 and 26 are disposed with their respective ends oppositely arranged, whereby the ring shaped handles 27 of the rods are located on diametrically opposed sides of the container. With the rods 25 and 26 in place, and generally there is no occasion for removing such lower pair of rods except for providing unobstructed access to the interior of the container in cleansing the same, the lower basket 20 is supported by the rods above the base portion of the container in the manner shown in Fig. 1. When a second basket is employed, it is of construction similar

to the lower basket described herein, and is supported by a second pair of transverse rods 31 and 32 (see Fig. 1), similar to rods 25 and 26 but preferably arranged to extend transversely with respect thereto. The rods 31 and 32 may be secured in place by keys similar to the key 29 shown in Fig. 1, which, as will be obvious, permits the ready withdrawal of the rods 31 and 32 after the upper basket has been removed from the container to enable the lower basket likewise to be removed. In the use of the device illustrated, initially only the lower basket 20 will be in position within the container. When a workman wishes to dispose of an oily rag or rags, he removes the cover 11 and drops the rags into the basket. When the lower basket is full or filled to a desired extent, the second basket (if the container is of the two basket capacity shown) may be placed in position after the rods 31 and 32 have been placed in position, and subsequent rags dropped into the upper basket.

Should oil or other fluid drip from the rags of the lower basket, it will drop into a drip pan indicated generally by the numeral 33. The drip pan is provided with a sheet metal bottom 34 provided with two opposed outwardly flaring side walls 35, a similar end wall 36, and a forward wall 37, the bottom and side walls being secured together to provide a fluid holding pan. The front wall 37 is of an area to overlap the receiving opening in the side wall of the container and preferably is provided with a suitable handle or hand grip 38 by which the pan may be withdrawn from the container; the pan, when in position within the container, being supported upon inverted channel shaped rails 39 attached to the bottom 12, and upon which rails the pan slides as it is moved into and out of position within the container. As viewed in Fig. 2, the bottom wall 34 of the pan is shown as provided with two pairs of spaced apart guide strips 40 which embrace the rails 39 and guide the pan in its sliding movements and locate the pan properly within the container.

The pan, as shown, is provided with a valve or drain cock in the bottom wall for drainage purposes when the pan is removed from the container, the valve being indicated generally by the numeral 41. In the form shown in Fig. 3, the valve comprises a collar or body 42 sealed in an opening in the base 34 and having a closure screw 43 which is adapted to be screwed down into a threaded passage for closing connected drain passages 44 and 44a located close to the upper surface of the base 34 and communicating through the pan bottom. By retracting the screw, the passages will be opened and the accumulated fluid will flow from the pan.

When the accumulation of refuse such as oily rags is such that the container is to be emptied, it may be carried away by a janitor or the like by gripping the handles 18. The basket or baskets may also be removed from the container and the drip pan withdrawn and the contents drained therefrom. If the container is of such size that it is more desirable to transport it by means of a conventional factory truck having horizontal lifting arms, such arms may be passed beneath the container between the runners or skids 13, elevated, and carted into place for discharge of its contents. Vehicles of the hoist type may grasp the loop handles 27 of the upper pair of rods 31 and 32 which are disposed diametrically opposite as are the handles of the lower pair of rods, or it may grip the handles 18, if preferred.

The above described construction provides a container and receptacles or baskets for the oily rags through which air currents can pass, while at the same time the masses of rags are protected against danger of ignition. The vertical strips or bumpers 17 prevent displacement of a basket so far from a central position as to contact the inner surface of the container and thus close the contacted portion to the ingress of air or subject the contents to ignition from the exterior of the container. The ventilation afforded to the collected refuse reduces the likelihood of spontaneous combustion occurring.

For the purpose of providing forced ventilation of the contents of a container, especially a container of larger capacity, an opening may be provided in a side wall thereof intermediate two of the spacing ribs 17 for example. The opening is adapted to be covered by a removable panel 45, as shown in Fig. 9, when forced ventilation is desirable; the panel being provided with a bracket providing a seat 46 for supporting an electrical motor 47 on the exterior of the container. On the shaft of the motor is mounted a fan 48, the shaft extending through an aperture in the panel 45 which has a foraminous or screened portion 49 for the free circulation of air therethrough as the fan operates. The fan is provided with a suitable sheet metal guard indicated generally by the numeral 50 provided with air passages 51 therein. When the motor is running, the fan will move outside air through the foraminous section 49 of the panel 45 and through the perforations 51 in the panel 50, while some of the same will move upwardly through an outlet 52 and some downwardly through outlet 53. Some of the air thus circulated through the container will pass through the basket or baskets in the container for preventing dangerous temperatures within the accumulated refuse within the baskets. A panel 54, as shown in Fig. 4, having openings therein, but without the motor operated fan construction may be employed in lieu of the panel 45 in instances where the forced aeration of the contents of the receptacles is not necessary.

While we have shown and described a container for waste useable in numerous locations, we do not wish to be restricted to the details illustrated except as so limited by the appended claims.

Having thus described our invention, what we claim as new and desire to secure by Letters Patent of the United States is:

1. A holder for used rags, inflammable refuse material and the like, comprising a cylindrical sheet metal container provided with louvered openings in the side walls to permit the lateral passage of air into and from the container, a removable imperforate cover for the container, a drip pan at the lower end of the container for catching fluid dripping from refuse above the pan, supporting means above the pan for a receptacle adapted to receive refuse deposited in the container when the cover thereof is removed, and an open top receptacle for refuse seated upon said supporting means and provided with foraminous side and bottom walls permitting free fluid therein to drip into said pan and for admitting passage into and from the receptacle of air flowing through the container for aeration of the receptacle contents.

2. A holder for used rags, inflammable refuse material or the like comprising a sheet metal container provided with a plurality of vertical

rows of louvered openings in the side walls to permit the lateral passage of air into and from the container, a removable imperforate cover for the container, a drip pan at the lower end of the container for catching fluid dripping from refuse above the pan, supporting means above the pan for a receptacle adapted to receive refuse deposited in the container when the cover thereof is removed, circumferentially spaced vertical members in the container for spacing receptacles on said supporting means away from the inner surface of the container, an open top receptacle for refuse seated upon said supporting means and provided with foraminous side and bottom walls so that free fluid in the refuse can drip from the receptacle into said pan and admitting passage into and from the receptacle of air flowing through the container for aeration of the receptacle contents.

3. A holder as defined in claim 2, and wherein said receptacle has a diametrically disposed raised base portion of foraminous material therein to provide for improved aeration of refuse material at the mid-portion of the receptacle.

4. A holder of the class described comprising a cylindrical sheet metal container provided with a plurality of circumferentially spaced vertical rows of louvered openings therein, a removable imperforate cover for the container, a laterally removable drip pan in the lower portion of the container for catching fluids dripping from waste material above the pan, a pair of rods above said pan extending transversely of the container for supporting thereon a waste material receptacle, vertical spacing members each disposed between adjacent rows of louver openings and secured to the interior of the container side wall for preventing contact of a receptacle with the inner wall of the container, and a receptacle for waste material adapted to seat on said rods above the drip pan and constrained by said spacing members against lateral shifting into contact with the container walls and comprising foraminous side and bottom walls enabling fluid to drip from the contents into said drip pan and admitting passage into the receptacle of air flowing transversely of the container through said louver openings.

5. A refuse holder comprising a metal container provided with a side wall having openings therein for admitting the flow of air into and from the container, a removable cover for the container, said side wall being provided with an opening near the bottom thereof for receiving a drip pan slidably horizontally into and from the container, a drip pan in the container slidably horizontally into and from the same via said opening, supporting means carried by said side wall above said drip pan, a receptacle for refuse having a side wall and a bottom and adapted to be placed in the container upon said supporting means when said cover is removed, said receptacle having openings in the side wall and bottom through which free fluid in the refuse deposited in the receptacle can drip into the subjacent pan and through which openings in the side wall and bottom air flowing through the openings in the container side wall can pass for aerating the container contents, and means for spacing the receptacle from the inner wall of the container and into vertical alignment with the pin.

6. A refuse holder comprising a metal container provided with a side wall having openings therein for admitting the flow of air into and

7
from the container, a removable cover for the container, transverse supporting means for supporting a refuse receptacle within the container, a refuse receptacle having an open top supported by the said means and having open mesh side and bottom walls for aeration of the contents by air flowing through the openings of the container side walls, and a motor operated fan unit mounted on the container side walls for producing movement of air through the container for aeration of the receptacle contents.

8
7. A refuse holder comprising a metal container provided with a side wall having openings therein for admitting the flow of air into and from the container, an imperforate removable cover for the container, transverse supporting means for supporting a refuse receptacle within the container, a refuse receptacle having an open top supported by said means and having open mesh side and bottom walls for aeration of the contents by air flowing through the openings of the container side walls, said side wall of the container comprising a removable panel section having a foraminous portion and provided with a motor support on the exterior and a foraminous fan guard on the interior, and a motor-fan unit comprising a motor on said support and a fan within said guard for inducing the flow of air through the openings of said panel into the container and through wall openings thereof for aeration of the receptacle contents.

8. A holder for used rags or the like comprising
